(57) **CLAIM**

The ornamental design for a toilet paper holder, as shown and described.

DESCRIPTION

FIG. 1 is a top, front right side perspective view of the toilet paper holder with a cover in a lowered position showing the new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a top, front right side perspective view of the toilet paper holder with the cover in a raised position.

The broken lines showing structural features are included for the purpose of illustrating non-claimed subject matter and form no part of the claimed design.
